UNITED STATES PATENT OFFICE.

EDSON F. GALLAUDET, OF PITTSBURG, PENNSYLVANIA.

DESIGN FOR A PUZZLE-BOX.

SPECIFICATION forming part of Design No. 26,909, dated April 13, 1897.

Application filed February 12, 1897. Serial No. 623,195. Term of patent 7 years.

To all whom it may concern:

Be it known that I, EDSON F. GALLAUDET, of Pittsburg, in the county of Allegheny and State of Pennsylvania, have invented a new 5 Design for a Puzzle-Box; and I do hereby declare the following, when taken in connection with the accompanying drawings and the letters of reference marked thereon, to be a full, clear, and exact description of the same, and 10 which said drawings constitute part of this specification, and represent, in—

Figure 1, a perspective view of my newly-designed puzzle-box. Fig. 2 is a view thereof in vertical central section. 15 My invention relates to an improved design for puzzle-boxes; and it consists in the configuration shown in the accompanying drawings and hereinafter described.

As shown in the accompanying illustration, 20 my newly-designed puzzle-box consists of an

annular band or fender A, inclosing a cone B, the center of which rises nearly to its upper edge.

The exterior face of this cone is encircled by a spiral path B', starting from a point near 25 its lower edge and terminating in a pocket B², formed in its top, the said path being practically uniform in width and in the depth of its convolutions, which gives the cone a stepped appearance. 30

I claim—

The design for a puzzle-box as herein shown and described.

In testimony whereof I have signed this specification in the presence of two subscribing witnesses. 35

EDSON F. GALLAUDET.
